UNITED STATES PATENT OFFICE.

OSCAR P. JOHNSON, OF NASHUA, NEW HAMPSHIRE.

PROCESS OF MOISTENING SHOE-UPPERS.

1,191,315.

Specification of Letters Patent. Patented July 18, 1916.

Application filed October 5, 1914. Serial No. 865,162.

To all whom it may concern:

Be it known that I, OSCAR P. JOHNSON, a citizen of the United States, residing at Nashua, in the county of Hillsboro and State of New Hampshire, have invented certain new and useful Improvements in Processes of Moistening Shoe-Uppers, of which the following is a specification.

This invention relates to the manufacture of boots and shoes, particularly of those in which the upper is of leather. It is a process of treating the fore part of the upper, especially the toe part, with steam of a relatively low temperature and at a low pressure applied from inside while the upper is held in such a position that whatever steam condenses will not run onto the other parts of the shoe and will not come in contact with the outside of the upper.

There is much difficulty in the pulling over and lasting operations on account of the leather cracking. The likelihood of such cracking or other damage is much reduced by properly softening the leather by the application of vaseline, water or vapor before it is pulled over and in performing these operations while the stock is moist. I am aware that prior to my invention water and water vapor have been used for this purpose but I believe that I am the first to use steam. I believe especially that I am the first to use steam applied underneath the upper while the unfinished shoe is held upright that is with the upper at the top and especially with the toe inclined downward.

My process may be carried out with various machines some of which are shown in the accompanying drawings in which—

Figure 1 is a side-elevation of a shoe being treated on a machine such as is described in Letters Patent issued to me March 11, 1913, No. 1,055,754 part of the above being shown in section. Fig. 2 is a plan view thereof. Fig. 3 is a side elevation showing a modification of the above named machine especially adapted for softening the toe cap. Fig. 4 is a plan view of part thereof. Fig. 5 is a front elevation of a hand operative device which may be used.

It is desirable in softening the fore part of shoe uppers that the outside which is

partly finished and is to be further finished should not be moistened or if it is moistened that such moistening should be uniform and not in streaks. If the upper is plunged into water or if the fore part of the unfinished shoe on the last is put into a chamber filled with water vapor or steam there will be more or less condensation and irregular saturation which will leave stains on the finished product. Such stains are very objectionable.

My process is especially desirable in preparing the upper for what are known as the side pulling or the bed lasting operations or for both.

A represents the last for a shoe and B the lining of the fore part thereof while C represents the upper and 10 the fore part of the upper. In Figs. 1 and 2, this is shown as tacked to the last at the heel and shank but free at the fore part.

D is a bench through which passes the vertical steam tube 11 into a steam cylinder 12 having a longitudinal lip 13 curved upward and backward as shown in Fig. 1 and having perforations 14 in the top as shown.

15 is a supporting bar which runs parallel with the lip 13 at such a distance and so at such a height that when the toe of the last is inserted under lip 13, the sole of the last or the inner sole 19 will rest on supporting bar 15 with the center of gravity behind it so that the last with the unfinished shoe will retain its position and so that this position will be with the toe inclining downward.

When the steam passes from its source through main pipe 11 and steam cylinder 12 into lip 13 and out through the perforations 14 at the top thereof, it comes directly in contact with the inside of the upper and the lining and is well distributed thereunder. Whatever steam may condense or whatever water may be carried along with it runs around the toe 16 of the last and drops off on the bench or ground without doing any injury and without staining the stock. Lip 13 is preferably curved in such a way as to fit with substantial closeness to the under part of the upper which is to be treated.

Before the first process of pulling over on the side pulling machine, the fore part

of the upper is spread out as shown in Figs. 1 and 2 and the lip 13 extends longitudinally so as to fit under it. In the next process, however, of forming the toe in what is known as the bed lasting operation, as shown in Figs. 3 and 4, the upper is tacked to the last A down to the beginning of the toe cap at 20. So tacking the upper naturally draws in the leather in such a way that it will not fit a longitudinal lip and I therefore use a lip of the shape shown at 21, in Figs. 3 and 4. In Figs. 3 and 4, the bench D is the same and also the main pipe 11. The steam cylinder 22 is substantially the same as 12 except that it has attached thereto instead of lip 13 one or more oblique tubes 23 each of which terminates in a hooded lip 21 of such shape that the toe 16 of the last can fit comfortably inside thereof and can preferably rest on the end 24 of the tube 23. As the toe 16 of the last rests on 24 and the leather of the upper extends over lip 21 in contact with the openings 25 therein, the supporting rod 26 can be placed behind the center of gravity of the last if desired. The operation is the same as in the first described apparatus, as when the steam passes through main pipe 11, steam cylinder 22, tube 23, lip 21 and out through outlets 25, it comes directly in contact with the inside of the upper leather of the toe and whatever drip there may be from condensation runs down underneath and drops off onto the bench or floor.

I may use a hand process such as shown in Fig. 5 if desired. In such case, I use a conductor 40 from any suitable source of low pressure steam and I attach at the end thereof a fish tail end or lip 41 having suitable outlets 42 in one face thereof. This lip 41 may be substantially flat or curved to conform roughly with the top of the last as preferred. In using my process with this device, the last A carrying the upper C may be held in the left hand L in such position that the toe will incline downward while the conductor 40 is held in the right hand M and the lip 41 is inserted between the upper and the last and is moved around to various positions as shown by the dotted lines until the whole of the part desired is properly moistened.

My process in general should be used before the upper is attached at the fore part to the inner sole. While it is preferable that in using my process the last should not only be in an upright position but with the toe inclining downward, satisfactory results may be obtained by holding the last in a horizontal position.

My process is the moistening of the fore part of the upper of a shoe, while on the last and while it is held in an upright position or with the forepart inclining downward, by

introducing steam under said upper or under the fore part thereof, especially wet steam of low pressure and low temperature. It includes any method by which that which is to be the inner side of the upper while in the under position is brought in contact with steam.

I claim:

1. The process of moistening the fore part of the upper of a shoe before it is attached to the inner sole which consists of placing it on a last, of holding the last in an upright position and of introducing steam under the upper between it and the last while the outer side of the upper is out of contact with said steam as described. 80

2. The process of moistening the upper of a shoe before it is attached to the inner sole which consists of holding the upper in an upright position and of introducing steam under it while the outer side of the upper is out of contact with said steam as described. 85

3. The process of moistening the upper of a shoe before it is attached to the inner sole which consists of placing it on a last, of holding the last in an upright position with the toe inclining downward, of inserting a steam conveyer with a plurality of small outlets at the top between the upper and the last, and of forcing steam through said outlets. 90

4. The process of moistening the upper of a shoe which consists of holding the upper in an upright position and of bringing the underside in contact with steam while the outer side of the upper is out of contact with said steam. 100

5. The process of moistening the upper of a shoe which consists of holding the upper in an upright position and of bringing the underside in contact with steam of low temperature and of low pressure while the outer side of the upper is out of contact with said steam. 105

6. The process of moistening the upper of a shoe before it is attached to the inner sole which consists of holding the upper in an upright position and of introducing under it wet steam of low pressure and of low temperature while the outer side of the upper is out of contact with said steam. 110

7. The process of moistening the inner side of the fore part of the upper of a shoe while on the last and before it is attached to the inner sole which consists of holding it in an upright position and of introducing wet steam of low pressure and of low temperature between it and the last while the outer side of the upper is out of contact with said steam as described. 120

8. The process of moistening the fore part of the upper of a shoe before it is attached to the inner sole, which consists of placing it on a last, and of introducing steam between the

upper and the last while the outer side of the upper is out of contact with said steam as described.

9. The process of moistening the fore part 5 of the upper of a shoe before it is attached to the inner sole, which consists of placing it on a last, and of introducing steam of low pressure and low temperature between the

upper and the last while the outer side of the upper is out of contact with said steam.

10

In testimony whereof I hereto affix my signature in presence of two witnesses.

OSCAR P. JOHNSON.
